UNITED STATES PATENT OFFICE.

THOMAS LUCIEN TALIAFERRO, OF CHICAGO, ILLINOIS.

METAL CONTAINER FOR SHOE-POLISH AND THE LIKE.

1,324,528.

Specification of Letters Patent.

Patented Dec. 9, 1919.

Application filed September 6, 1919. Serial No. 322,042.

To all whom it may concern:

Be it known that I, THOMAS L. TALIAFERRO, a citizen of the United States, residing at Chicago, in the county of Cook, State 5 of Illinois, have invented certain new and useful Improvements in Metal Containers for Shoe-Polish and the like, of which the following is a description, reference being had to the accompanying drawing and to the 10 figures of reference marked thereon.

The invention relates to new and useful improvements in metal containers, and more particularly to a container having a body portion with a slip cover frictionally engaging the same in which shoe polish or the like is stored.

An object of the invention is to provide a container of the above character with a cover having the lower edge portion thereof 20 bent outwardly and thence inwardly to strengthen the lower edge and to form a shoulder which causes the cover to be quickly released from the body portion of the container when rapped lightly at any 25 point along said strengthened lower edge.

In the drawings, which show by way of illustration one embodiment of the invention:

Figure 1 is a side view of a box or container embodying my improvements;

Fig. 2 is a similar view, but showing on an exaggerated scale the shaping of the cover when struck a light blow at the strengthened lower edge thereof;

Fig. 3 is a vertical sectional view through one side of the box with the parts as in Fig. 1;

Fig. 4 is a view similar to Fig. 3, but with the parts as positioned in Fig. 2.

In carrying out the invention, I have prepared a container having a body portion of the usual construction, said body portion having a vertical side wall, the upper edge of which is turned inwardly to facilitate the placing of the cover on the box and the removal of the same, and said body portion is also provided with a rib extending parallel with the top edge of the body portion for limiting the downward movement of the cover onto said body portion. Said cover embodies the new features of my invention, and these features consist in bending outwardly the lower edge of the cover to form a shoulder, and thence bending said edge inwardly to strengthen the same. This strengthened edge extends outwardly beyond the rib on

the body portion so that it may be readily struck a light blow at any point, and the striking of this edge with light blows at any point quickly releases the cover from the 60 container.

Referring more in detail to the drawings, I have shown my improved container or box for storing shoe polish or the like as consisting of a body portion 1 having a vertical 65 side wall 2 turned slightly in at the upper edge, as indicated at 3. Intermediate the upper and lower ends of the side wall there is an annular rib 4 which projects outwardly. Said rib is parallel with the top edge of the 70 body portion of the container and serves as a limiting stop for the cover which is a slip-on cover frictionally engaging the outer wall of said body portion.

The cover is indicated at 5. Said cover 75 has a downwardly projecting flange or vertical wall 6 which is bent outwardly, as at 7, to form a shoulder 8. Said outwardly bent portion is also bent inwardly again, as at 9, thus forming a strengthened edge with 80 the shoulder 8 just at the inner part of said strengthened edge. The external diameter of the extreme lower edge of the cover is slightly greater than the external diameter 85 of the body portion at the rib 4. Said strengthened edge may be rapped by any suitable instrument at any point along the same. A light blow on the cover at such point causes the upper part of the vertical wall of the body portion to spring inwardly 90 slightly, as indicated in Fig. 4 of the drawings. The shoulder 8, through this springing of the body portion, creeps up on said vertical wall and as the light blows are continued, said shoulder will continue to creep 95 up the wall until the shoulder is finally released.

Another effect which is accomplished by striking this lower strengthened edge of the cover is the slight distorting of the 100 cover, as indicated in Fig. 2 of the drawings, along the line of the lower edge. The point *a*, where the blow is struck, approaches the point *b* diametrically opposite the point *a* and as these points approach each other, 105 the points *c* at opposite sides of the cover and at ninety degrees or thereabout from the points *a* and *b* will be raised upwardly, the lower edge of the cover taking a curved line shape. This upward movement at the 110 points *c* tends to release the cover at the sides. The turning in of the edge and

strengthening of the same increases this buckling effect which releases the cover at the points *c-c*. This buckling of the cover, together with the creeping of the shoulder 5 upwardly on the vertical wall of the body portion, quickly releases the cover although it may be very firmly seated on said body portion.

It is obvious that minor changes in the 10 details of construction and the shaping of the parts may be made without departing from the spirit of the invention which consists primarily in the outwardly bent lower edge infolded to strengthen the same, 15 which edge extends diametrically outwardly beyond the extreme outer parts of the body portion so that said strengthening edge may be struck light blows for the purpose of causing the cover to creep up on the body 20 portion and be released therefrom.

Having thus described the invention, what I claim as new and desire to secure by Letters-Patent is:—

1. A metal container comprising a body 25 portion having a vertical wall and a slip

cover frictionally engaging the outer face of said vertical wall, said cover having its lower portion bent outwardly away from said wall and strengthened whereby the edge may be struck light blows for releasing the cover from the body portion of the container. 30

2. A metal container comprising a body portion having a vertical wall and a slip cover frictionally engaging the outer face of 35 said vertical wall, said cover having its lower portion bent outwardly away from said wall and strengthened by folding said vertical wall of the body portion having a rib formed therein parallel with the upper edge 40 of said body portion for limiting the downward movement of the cover, said outwardly bent portion of the cover extending beyond the extreme outer edge of said rib whereby said strengthened edge of the cover may be 45 struck light blows for releasing the cover from the body portion.

In testimony whereof I affix my signature.

THOMAS LUCIEN TALIAFERRO.
